UNITED STATES PATENT OFFICE

JOHN H. McCANN, OF CHICAGO, ILLINOIS

PROTECTIVE COVER FOR PLUMBING FIXTURES

Application filed March 27, 1929. Serial No. 350,284.

This invention relates to coverings for porcelain or vitreous coated plumbing fixtures, such as bath tubs, lavatories, sinks, etc. and more particularly to coverings that are 5 adapted to be temporarily applied to the fittings for protecting the same while the building is under construction. Many of these fixtures, especially bath tubs, are "built-in", which necessitates their installation prior to the completion of plastering or tile-setting in the bath room, and some times even before the partitions are fixed in position. Under such conditions the fixtures are likely to be damaged by the workmen; accordingly it is desirable that some form of covering be provided to prevent such injury.

The primary object of this invention is to provide an improved covering with means to prevent its unauthorized removal from the fixture, thus insuring the latter against willful abuse, neglect or carelessness during construction work. Another object is to provide an improved covering, especially suited for fixtures of the "built-in" type that fully 25 covers the fixture before plastering or tile-setting on the adjacent walls and adapted to be adjusted by authorized persons to provide clearance for the plastering or tile-setting while still protecting the remaining portion of the fixture. A further object is to produce an improved covering that is simple, light, strong and durable and capable of use over and over again. It consists in certain features and elements of construction herein 30 shown and described, as indicated by the claims.

In the drawings:

Figure 1 is a top plan view of a cover embodying this invention as applied to a built-in bath tub, showing in section the adjacent walls of the room or recess, and with the cover adjusted to fit against the rough finished walls.

Figure 2 is a similar top plan view, but showing the cover adjusted to provide clearance for finishing work on the walls.

Figure 3 is a front elevation of the tub with the cover applied thereto, certain portions being broken away to reveal details of construction, particularly the locking means.

Figure 4 is an end elevation of the tub taken as indicated at line 4-4 on Figure 3 and with a portion broken away to show the locking means.

Figure 5 is a detail section taken as indicated at line 5-5 on Figure 1.

Figure 6 is a front elevation of the lavatory bowl fitting with a cover embodying this invention.

Figure 7 is a side elevation of the same showing the adjacent wall in section.

Figure 8 is a front elevation of a pedestal type lavatory fitting with a protective cover.

Figure 9 is a rear elevation of the same with a portion broken away to condense the view.

Figure 10 is a partial elevation of a pedestal lavatory with a modified form of cover applied thereto.

Figure 11 is a bottom plan view of the cover shown in Figure 10, and is taken as a section at line 11-11 thereon.

Figure 12 is a top plan view of a protective cover as applied to a closet bowl.

Figure 13 is a side elevation of the same with parts broken away and shown in section.

Figure 14 is a front elevation of a kitchen sink with a protective cover applied.

Figure 15 is an end elevation of the same with the adjacent wall shown in section.

For illustrative purposes the present invention is shown in Figures 1 to 5 as applied to a conventional design of a "built-in" bath tub indicated at 1. When installing this type of tub, it is positioned with one or more of its lateral surfaces closely adjacent a corresponding number of rough walls, as indicated at 2; and as herein shown, the tub is surrounded by walls at both ends and at one side. As is well known, the finished surface of the wall as indicated at 2^a, whether plaster, tile or the like, is applied so as to partially imbed the adjacent edge portions of the tub with the final layer of the wall overlapping the outer marginal portions of the tub. The protective cover embodying this invention is preferably applied prior to the surfacing of the walls so as to insure protection of the fixture from the day when it is installed until completion and final inspection of the building. The protec-

tive covering includes a main cover portion, 3, substantially enclosing the cavity of the tub, and supplemental cover portions, 4, of the same width, adjustably connected to each end 5 of the main cover portion for extension longitudinally toward and away from the adjacent walls. This adjustment is obtained by means of button head bolts, 5, extending down through the main cover section, through slots, 10 6, in said supplemental portions, with wing nuts, 7, on the inner ends of the bolts for firmly clamping the supplemental portions in any position of adjustment. The ends of the main cover section may be upwardly offset 15 as at 3^a, (see Figure 5) so that the under surface of these supplemental extensible portions is in substantially the same plane as the under surface of the main cover portion.

The front lateral surface of the tub should 20 also be protected against injury while work is being done about the building, and for this purpose I provide an independent covering, 8, comprising a front skirt portion, 9, substantially covering the exposed lateral area, 25 and continuing at its upper edge in a transverse portion, 10, overlapping the adjacent upper edge of the tub and thence downwardly into a depending flap, 11, disposed against the inner surface of the tub as seen in Figure 30 4. The shape of this covering member is such as to tend to secure it in position so that it is removable only in an upward direction. Preferably the entire inner surface of the covering member, 8, is lined with suitable 35 padding such as felt or the like, as indicated at 12, to protect the finished surface of the tub against abrasion.

The cover proper, comprising the main portion, 3, and supplemental portions, 4, is positioned so that its front edge rests upon the top of covering member, 8, and a U-shaped gasket or pad member, 13, may be placed around the other three upper edges of the tub to support the other edges of the cover in substantially level position. This gasket preferably includes a reinforcement, 14, such as metal, fibre, or the like, to the under side of which is secured suitable lining, 15, such as felt, so that the weight of the cover proper, 50 plus the weight of workmen or tools, etc. will not injure the finished edges of the tub. When the finish of the wall is tile, after setting, it is usually washed with acid; this acid heretofore has frequently dripped or seeped 55 down into the tub, and often caused blemishing or marring of the finished surface; but the felt or lining of the gasket tends to seal the tub to protect it from the acid.

In order to insure that the covering shall 60 effectively serve the purpose intended, it is preferably locked to the fixture in a manner to prevent its unauthorized removal. The cover proper is held fast on the tub against upward movement by securing means comprising an upwardly extending tie strut in-

cluding a rod, 18, projecting through a horizontal flange, 19, of a fastening member, 20, seated over the drain outlet, 21, at the bottom of the tub. The lower end of the rod is formed with a hook portion, 22, adapted to engage under a cross bar, 23, of the drain fitting, 24. Threaded on said rod is a nut, 25, adapted to be screwed tight against the upper side of flange, 19, for firmly securing the rod in hooked position. A second rod, 26, is connected in alignment with rod, 18, by a turnbuckle, 27, for varying the effective length of the combined rods. The upper end of the rod, 26, is formed with a head, 28, adapted to be engaged in the seat formed in the bracket, 30, secured to the under side of the cover, 3. As may be seen in Figure 1, when the cover is positioned in the tub with its rear edge abutting the rough surface back wall, this bracket, 30, approximately aligns 85 itself with the longitudinal center of the tub, thus, the combined rods, 18 and 26, will assume a substantially vertical position for holding the cover down.

It is desirable that the same covering may 90 be used for either right or left hand tubs, that is, with the drain and faucets at either right or left end, as may be required; so a second bracket, 31, is secured to the under side of the cover adjacent bracket 30, in a position to align with the longitudinal center plane of the tub when the cover is reversed end for end. To practically prevent the cover being sprung up at the end remote from the tie, 18, a second angularly disposed tie strut is connected to the under side of the cover. This tie strut includes a pair of rods, 33 and 34, connected by a turnbuckle, 35, for varying their effective combined length. This strut, 95 extends obliquely upward from the drain toward the rear end of the tub; the lower end of rod 33 is threaded and secured in the lug, 36, of the fastening member, 20, by a nut, 37, and the upper end of rod 34 is formed with a head, 38, adapted to engage in a seat formed in a bracket, 39, secured to the under side of cover portion 3 on its longitudinal center.

To permit access to, and manipulation of the turnbuckles of the tie struts for securing or releasing the cover on the tub, an opening 100 is formed in the cover portion 3 which is controlled by a hinged lid, 40. The lid has a hasp, 41, secured thereto, cooperating with a shackle, 42, on the top of the cover and in which is secured a padlock, 43. This same opening also controls access to the clamping bolts for securing the extensible cover portions, 4, in adjusted position.

When the covering is applied to the tub and the gasket placed around the other upper edges of the tub, then the skirt is first placed on the front side of the tub, the cover proper is positioned on top of the gasket and skirt, with its rear edge abutting the rough back wall, and the supplemental cover portions, 4, 110

extended to abut the side walls at the ends of the tub, as seen in Figure 1, said parts, 4, being made fast by the clamping bolts, 5. The two tie rod struts are then adjusted to hold the cover tight on the tub, by access through the door, 40, which is then padlocked to prevent unauthorized removal of the covering. When it is desired to finish the walls of the bath room, the authorized person then unlocks the cover door, 40, releases the tie struts, and moves the cover proper away from the back wall the proper distance, and at the same time the supplemental portions, 4, are retracted and clamped in position to afford proper clearance for finishing the side walls; the tie struts are again made taut to hold the cover in this new position (as shown in Figure 2) and the access door, 40, is relocked. If the extensions, 4, and the cover itself have been moved some distance from the wall to give ample room for the finishing work, it may be desirable to re-adjust the cover again after this work is completed, moving it close to the finished surface of the wall and thus completely protecting the upwardly exposed surfaces of the tub.

It may be understood that in designing this covering, it may be dimensioned so that when the cover is moved forward away from the back wall for plastering or tile-setting, the bracket, 31, will substantially align with the vertical center plane of the tub, and the head of the rod, 26, may then be shifted to that bracket, if desired. Thus this combined strut may be disposed in substantially vertical position when the cover is at either position of adjustment. And when the cover is reversed end for end for use with a tub of opposite hand, the brackets, 30 and 31, may be used in converse order. It is apparent that the covering is capable of such slight modification and variation as to readily adapt it for use with installations of various character, as for example, where the tub is placed in a room, with only one or two sides against the walls and two or even three sides exposed. Of course, where the tub is positioned away from the walls there will be no necessity for adjusting the extent of the cover during the progress of work on the building, but the fact that it can be locked in place against unauthorized removal will greatly increase the safety of the fixtures during the course of building construction.

As represented in Figures 6 and 7, the fixture is a lavatory, 50, of the type adapted to be mounted adjacent and supported by an upright wall, 51, preferably prior to plastering or setting tile of said wall as indicated at 51^a, because of the anchorage of the fixture to the wall. The fixture is encased by a protective covering, 52, of any suitable material such as wood or sheet metal and is constructed as a rigid boxlike structure having a top, 53, with depending flanges, 54, on the front and sides, the covering thus opening downwardly and toward the wall; it being understood that if desired the end adjacent the wall may also be closed if desired in cases where the fixture is spaced away from the wall. By the construction shown, the covering may be removed only in a forward or upward direction. To prevent its unauthorized removal, the covering is locked to the fixture by a flexible tie member herein shown as a chain 55, rigidly attached at one end to a side flange, 54, and is then trained around the back under side of the bowl portion, 56, of the fixture with the other end of the chain secured to a shackle, 57, on the opposite side flap of the covering by means of a padlock, 58. To prevent injury to the finished surface of the bowl by abrasion, the portion of the chain in contact with the bowl is encased in a flexible sheath, 59, of leather, rubber or other suitable material. Some fixtures are installed equipped with faucet fittings, 60, and to insure their protection, the covering, 52 may be formed with an upwardly offset portion, 61. It will be understood that the interior of the covering is lined with some suitable material such as felt (not shown) to protect the finished surface of the fixture.

The fixture illustrated in Figures 8 and 9 is a pedestal type lavatory, 65, having a pedestal or supporting base, 66, adapted to be mounted on the floor. The covering, 67, for this fixture is similar to that shown in Figures 6 and 7, and includes depending flanges or flaps, 68, on the front and sides. Secured to the depending flaps adjacent their lower edges are angle clips, 69, having inwardly extending horizontal flanges, 70, positioned to clear the bottom edges of the lavatory when the covering is slid into place thereon, and in such position adapted to prevent upward removal of the covering. Threaded through the flanges, 70, are set screws, 71, to be projected into the cavity, 72, of the under side of the fixture for firmly securing the cover in place against shifting movement. The covering is locked to the fixture to preclude unauthorized removal by the same arrangement as shown in Figures 6 and 7; the chain, 73, being connected to one side flap, 68, extends around the back of the pedestal, 66, and is secured to the opposite side flap by a padlock, 74; a sheath, 75, covering the intermediate portion of the chain to protect the pedestal against abrasion.

Figures 10 and 11 illustrate a modified form of covering, 76, for a pedestal type of lavatory, 77. In this construction the covering is constructed with a rigid downwardly open box-like structure having a top, 78, and depending flanges, 79, on all four sides, and hingedly connected to the lower edge of each flange, 79, preferably at or slightly below the lower edge of the lavatory proper is a supplemental flap, 80, adapted to be swung

inwardly toward the pedestal of the fixture. An eyelet, 81, is secured to the inner side of each flap adjacent its longitudinal center, and trained through said eyelet is a flexible tie member, shown as a chain, 82. Thus when the chain is drawn taut, the supplemental flaps, 80, are pulled inwardly as shown in Figure 10, and the ends of the chain are secured together by a padlock, 83, for preventing unauthorized removal of the protective covering in any lateral or upward direction.

In Figures 12 and 13 a closet bowl type of fixture, 86, is almost totally encased by a protective covering, 87, which comprises a top portion, 88, hingedly connected depending front and side flanges or flaps, 89, and supplemental flaps, 90, hingedly connected to their lower edges. Trained through eyelets, 81, secured on the outer surface of said supplemental flaps is a flexible chain, 92, adapted when drawn taut to move the supplemental flaps inwardly so as to be in position to contact with the inwardly sloping under surface, 86^a, of the fixture and thus prevent upward removal of said covering, while the removal thereof in a forward direction is precluded by the chain proper contacting with the rear of the fixture, a padlock, 93, being provided to connect the ends of the chain, thus locking the cover to the fixture against unauthorized removal; a sheath, 94, surrounds the portion of the chain contacting the rear of the fixture to prevent the surface from being damaged. It will be understood that if desired the flanges, 89, could be formed rigid with the cover top, 88, or the supplemental flaps, 90, may be formed rigid with respect to their supporting flanges, 89, provided the former are disposed at a suitable inward inclination with respect to the latter so that they may be swung about the hinge connections to the top to a position to engage the under side, 86^a, of the bowl; but the double hinging permits more compact folding of the cover when out of use. The rear edge of the top is provided with an open notch, 95, to provide clearance for the upwardly extending water supply pipe, 96.

As a separate or additional means for precluding unauthorized removal of the protective covering on a fixture of this type, the top, 88, is formed with a depressed well, 97, a substantial distance below the top surface, and extending downwardly through the bottom of the well is a hook member, 98, having a laterally extending hook portion, 99, adapted to be moved into engagement with the under side of the obliquely sloping shelf portion, 100, and firmly held in such position by a nut, 101, threaded on the upper end of said member, 98, and abutting the upper side of the bottom wall of said depression. To insure against backing off the nut, 101, and releasing the hook member, a padlock, 102,

has its shackle entered in an aperture, 103, in the upper end of the member, 99, just above the nut when the same is screwed home.

The fixture illustrated in Figures 14 and 15 is a sink, 105, of the type adapted to be mounted directly against the finished surface of an upright wall, 106, on which it is mounted. The fixture is fully enclosed by a protective covering, 107, of box-like form having a top, 108, and rigid depending flanges, 109 and 110, on the side and ends respectively; the open side facing the wall, 106. The top is provided with an upwardly offset portion, 111, to accommodate the upright apron, 112, of the fixture; this offset portion preferably being large enough to accommodate fixtures of this type that are installed equipped with faucet fittings, 113.

The depending flanges are each provided with angle clips, 114, having inwardly projecting lugs, 115, and adapted to extend below and clear of the lower edge of the fixture when the covering is placed thereon. Set screws, 116, are carried on each lug, 115, and adapted to engage the under side of the fixture for securing the covering against shifting. It will be understood that this same covering is capable of use with sinks of this general type, having a supporting leg or legs. With such construction the covering may be removed only in a lateral direction away from the wall. One end of a chain, 117, is permanently secured to the side flap, 109; thence the chain is trained around the drain or waste pipe, 118, and the other end is secured to a shackle, 119, on the side wall by a padlock, 120, by means of which the protective covering is locked to the fixture against unauthorized removal.

It will be understood that in all the protective coverings for the various fixtures illustrated in Figures 6 to 15, the interior surfaces of the coverings are lined with suitable material such as felt, so as to protect the finished surfaces of the fixtures against injury by abrasion such as might occur in placing or removing the covering from the fixture, or due to a limited amount of movement even when it is locked in place thereon. In some localities it is common practice to partially fill a tub with sawdust to protect the enamel during construction work and where the locking of the protective covering is not deemed essential, this practice may be supplemented by the use of one or more skirt members such as that shown at 8, which will serve to protect the lateral surfaces more effectively than anything heretofore provided.

I claim:—

1. In combination with a plumbing fixture having an upwardly open cavity and a laterally exposed surface, a protective cover including a main cover portion dimensioned to serve as a closure for said cavity and a de-

pending flange adapted to substantially cover said laterally exposed surface of the fixture; and locking means for securing said cover against unauthorized removal.

- 5 2. In combination with a plumbing fixture installed adjacent a wall and provided with an upwardly open cavity, a cover comprising a main cover portion dimensioned to serve as a closure for said cavity and a supplemental portion attached to the main portion and adjustable with respect thereto for varying its lateral extent with respect to the wall, means for firmly securing said supplemental portion to the main portion in any position of adjustment, means connected to the under side of the main cover portion and anchored to the fixture for holding the cover against upward movement, and single locking means for controlling access to both said securing means and holding means.
- 10 3. In the combination defined in claim 2, said depending skirt having a transversely extending portion at its upper edge adapted to engage the upper edge of the fixture.
- 15 4. In combination with a plumbing fixture having an upwardly open cavity, a temporary protective cover dimensioned to serve as a closure for said cavity, means extending wholly from the under side of said cover, adapted to be anchored to the fixture and provided with securing means disposed within the cavity and adjustable for holding the cover against upward movement, said cover having an opening arranged to permit access to the securing means and a closure for said opening provided with locking means adapted to prevent unauthorized access to the securing means.
- 20 5. In combination with a bath tub provided with an upwardly open cavity and having a laterally exposed outer surface, a temporary protective cover including a rigid depending skirt positioned to overlie substantially the entire laterally exposed surface of the fixture and a main cover section dimensioned to serve as a closure for the cavity and adapted to engage the rigid skirt, means connected to the under side of the main cover section and anchored in the cavity of the tub for holding said cover section and skirt firmly in position, and means for precluding unauthorized access to the cover holding means.
- 25 6. In combination with a bath tub provided with an upwardly open cavity and a laterally exposed surface, a temporary protective cover, including a covering element having a substantially rigid depending skirt positioned to overlie the laterally exposed surface, a transversely extending portion at its upper edge overlying the upper edge of the tub, and means secured to said covering element and arranged to engage the inner surface of the tub cavity to preclude removal thereof in lateral direction, a main cover portion dimensioned to serve as a closure for the

tub cavity and engageable with the transversely extending portion of the covering element, and means for holding said main cover portion and covering element in place on the tub.
